UNITED STATES PATENT OFFICE.

JOHN L. REID, OF CHICAGO, ILLINOIS.

GAS HEATER AND BURNER.

SPECIFICATION forming part of Letters Patent No. 793,908, dated July 4, 1905.

Application filed May 31, 1904. Serial No. 210,347.

To all whom it may concern:

Be it known that I, JOHN L. REID, a citizen of the United States, residing at Chicago, in the county of Cook and State of Illinois, have 5 invented a certain new and useful Improvement in Gas Heaters and Burners, of which the following is a specification.

My invention relates to gas heaters and burners, and has for its object to provide new 10 and improved constructions for apparatus of that class.

My invention is illustrated in the accompanying drawings, wherein—

Figure 1 is a vertical sectional view with 15 certain parts shown in elevation. Fig. 2 is a vertical sectional view through the lower portion of the heater. Fig. 3 is a horizontal sectional view on line 3 3 of Fig. 2, with a part of the upper casing of the burner broken 20 away. Fig. 4 is a sectional view on line 4 4 of Fig. 2. Fig. 5 is a similar view on line 5 5 of Fig. 1, and Fig. 6 is a similar view on line 6 6 of Fig. 1.

Like letters of reference indicate like parts 25 in all the drawings.

The lower part of the heater is composed of a preferably cylindrical outer casing A, having the flange A'. This cylindrical part rests upon a base-plate B against an annular 30 projection B' thereupon, and this base-plate B is supported in any desired manner, as by the legs C, which may be bolted to the base-plate B by the bolts C' and the nuts C''. The above parts are preferably made of cast-iron, 35 but of course may be made of any desired material.

The upper part of the heater is formed of a cylindrical casing D, preferably of sheet metal, riveted to the cylindrical part A and 40 resting upon the flange A'. The casing D has leading from it near its upper end the smoke-pipe D'. On the inside of the outer casing A are wings or ribs A'' A'', which are inclined from the vertical and are of decreasing width 45 from top to bottom. These are preferably integral with the casing A.

E is the burner and is in the form of a hollow ring flattened on four sides, as shown. This is preferably composed of a lower cast- 50 ing E' and an upper casting E'', each having

lugs E''' E''' on their perimeters, through which pass the bolts E' E', which securely hold the two parts together. The base-plate B has a circular opening therein a trifle larger in diameter than the burner E which received such 55 burner, the ends of the bolts E' E' resting upon this base-plate, so as to support the burner in position. The burner is pierced by a series of perforations E''' E''' on its inner circumference and by a like series of perforations E''' E''' on the outer circumference. These serve to emit the gas to be burned and are preferably obliquely directed. The gas enters the burner by the supply-pipe F and through a valve. This valve is preferably of 60 the needle-valve type and constructed with an outer shell G, open at one end, and within such shell is an inner casing G', to which the supply-pipe F leads. The inner shell G' is perforated at each end for the valve-stem G'', its 65 inner perforation having a valve-seat. The outer end of the inner shell G' is provided with the cap G''' with a screw-threaded perforation therein, through which passes the stem G'', which is likewise threaded. Suitable packing G''' makes a gas-tight connection at this point. The stem G'' has the hand-grip G''' and also a disk G'', which is held in position thereon by the set-screw G''. This disk G'' is given such a position 70 on the stem G'' that it operates to close the open end of casing G when the pointed end of the stem G'' is seated against the aperture in the inner shell. By turning the hand-grip G''' both valves are opened, and the gas passes 75 from the inner to the outer casing, and air is drawn into the outer casing around the disk G'', is mixed with the gas, and this mixture passes up into the burner E. The casing G has a screw-threaded neck G''' which connects 80 it to the pipe G'', leading into the burner E. In order to insure the complete mixture of the gas and air, I preferably place within the burner E a spiral spring E'', through which the incoming mixture is directed by the hood 85 E'', which may be made in the form of an inverted box open at each end, and is placed within the burner E over the terminus of the pipe G''. The spring E'' may be made to terminate at each end of this hood. Within the 90

casing A is an inner casing H, which is preferably made of cast-iron and in the shape of an inverted frustum of a cone and provided with the flange H', which is preferably curved 5 in cross-section, as shown. On the outer side of the casing H are the wings or ribs H² H², which are of increasing width from top to bottom and are inclined from the vertical in the direction opposite to the corresponding construction 10 on the inner face of the casing A. Between these two ribbed walls is formed the combustion-chamber of the heater, at the bottom of which is the burner E. On the inner side of the casing H are vertical triangular-shaped ribs H³ H³, here shown as four in number, and against these rests the inverted hollow deflecting-cone J, which is preferably made of sheet metal. To the casing H is riveted 15 a cylindrical inner casing K, made of sheet metal, which divides the upper portion of the heater into two chambers. The casings K and D are secured together by an annular cap-piece L, resting upon the casing D and secured to casing K by the inwardly-extending 20 connecting-ring L' and by the tie-bolts L² L². In order to hold all of these parts securely in position, I provide the tie-rods M, shown here as three in number, which extend through the outer chambers from the cap-piece L down through the base-plate B.

In the lower part of casing A there is a perforation A³ closed by the door N, pivoted at N' and provided with the lug N², by which it is manipulated. By means of this door the 35 gas may be ignited. I also provide casing D with a mica window D².

In order that the products of combustion shall not escape too rapidly through the heater before having performed their work, the upper 40 portion of the combustion-chamber, between the inner and outer casings D and K, is divided by a number of perforated horizontal rings. There may be any number of these rings, as desired—as, for instance, the three 45 O, O', and O² shown in this construction. These rings are preferably provided with inner vertical flanges, by means of which they are secured to the inner casing K. These rings have each a series of apertures, which 50 may be semicircular indentations on their inner and outer circumferences, as shown in Figs. 5 and 6, the apertures being differently positioned in the different rings. As shown in Fig. 5, the upper ring has these indentations on its inner circumference, as shown 55 at O³. In the ring O' next below the apertures will be differently located—as, for example, between the projections on ring O' of the apertures O² in the ring above, as is shown 60 at O⁴ by dotted lines in Fig. 5. In the lowest ring these apertures may be made in the outer circumference, as shown at O⁵ in Fig. 6. The products of combustion will therefore be obliged to follow a somewhat circuitous course 65 upward through the combustion-chamber. It

will be obvious in carrying out this purpose that the above arrangement of apertures might be considerably varied, so I do not limit myself to the precise position of the apertures as above shown.

In order that there should be a continuous draft from the lower combustion-chamber to the smoke-pipe D', I provide within the upper combustion-chamber a direct flue O⁶, which may be constructed by the curved partition 70 O', which rests upon one of the wings A² and extends to a point near the opening of the smoke-pipe. This inclosed flue will carry a portion of the hot products of combustion 75 directly from the lower combustion-chamber 80 into the smoke-pipe D', and by heating the same will tend to prevent the condensation of moisture and the consequent setback of water from the chimney into the heater. In the space between the legs of the heater and under the burner E, I preferably place a protecting and draft device P, which may be made of any sort of sheet metal and is preferably in the form of a frustum of a cone. This device is provided with the horizontal 85 flange portion P' and is supported in any desired manner to the body of the stove—as, for example, by the tie-irons P². To the under side of the flange P' is secured, by the brackets P³ P³, a circular disk P⁴. The extended portions P' serve to protect the floor 90 from the intense heat of the burner, and the device also, which may be made to extend very close to the floor, serves to draw air into the heater from the lowest and consequently the 95 coldest portion of the room to be heated.

I have described with some particularity one form of construction which embodies my invention, but it will be obvious that there might be a wide variance from the forms and devices set forth without departing from the broad spirit of my invention. For example, the heater might be given any other shape than cylindrical and might be of a considerably greater size than here shown. The heater, 100 for instance, is well adapted when constructed upon a large scale to heat a whole building. Consequently I do not limit myself to the particular forms, devices, and constructions above set forth.

The use and operation of my heater are as follows: To start the heater, the hand-grip G⁵ is turned, opening at once the gas and the air valve. The air and gas are mixed within the outer shell G and pass up into the burner through the pipe G⁹ and are directed by the hood E⁸ into the central part of the spiral coil E⁷, where they are thoroughly mixed. The gas emitted through the apertures E⁵ E⁵ and E⁶ E⁶ is lighted through the lighting-aperture 110 A³, the flames being directed against the ribbed walls of A and H. The position and direction of these ribs tend to hold back the products of combustion, and the ribs also increase 115 the area of radiation. The curved flange H' 120

also tends to hold back the heat within the lower "combustion-chamber," as it may be called, and the same effect is brought about in the upper chamber by the staggered arrangement of the apertures in rings O, O', and O''. The peculiar arrangement of these apertures directs the rising products of combustion first to the inner and then to the outer casing of the heater. The air to be heated with-
 5 in the heater is drawn up around the disk P¹ from a place in the room very near to the floor, where the air is obviously the coldest. It passes up through the conical device P into the center chamber formed by the shell H and the upper and inner casing K, being deflected by the inverted cone J, so as to form a draft around the inner side of the casing K. This air will be heated by contact with the walls and by radiation, and in order to
 10 aid in the accomplishment of this purpose the center chamber is given a diminished diameter at its upper end by the extending cap-piece L. The back flue O'', as described, keeps up a continuous flow of the hot products of
 15 combustion from a place near the burner directly to the smoke-pipe, thereby keeping up a steady draft and also preventing condensation and the setback of water from the chimney. The flange portion P' of the device P
 20 protects the floor from the severe heat of the burner besides serving to increase the draft, as described. It will be observed also that the burner E is easily removable for repair, it resting merely upon the base-plate B. Being formed of two parts, it may easily be taken apart when required.

The heater is adapted to burn ordinary illuminating-gas or natural gas or any fluid of like nature.
 25 By the above-described and by a similar construction of parts adapted to varying circumstances I am able to get a very complete combustion of gas and a great heating capacity at moderate expense.
 30 It is one of the purposes of my invention to secure a circulation of air in the room being heated through the heater. It is very important that this circulation should be as widely extended as possible and that the air which enters the heater should be drawn from the coldest part of the room—that is to say, the lower part. To accomplish these results, I use the device P, which serves the double purpose of drawing the air from near the floor and at a point at some distance from the burner, and also protects the floor by its flaring part and prevents the highly-heated air immediately surrounding the burner and its neighboring parts from being drawn up through the stove. The part P, in effect, is an extension of the draft or air chamber beyond the combustion-chamber and burner, so that its opening is brought near to the floor.

I claim—

65 1. In a gas-heater the combination of an

outer shell surrounding a combustion-chamber, an inner shell of gradually-diminished diameter at its lower end forming an air-chamber in such combustion-chamber, and a flange on the inner shell of substantial uniform width thereabout, near the place where the inner shell begins to be reduced in diameter, extending into the combustion-chamber so as to hold back the products of combustion in the lower part of such chamber. 70

2. In a gas-heater the combination of an outer shell with an inner shell arranged within the outer shell so as to leave a space between, such space forming a combustion-chamber, and ribs on the outer shell inclined from the vertical and projecting into such combustion-chamber. 75

3. In a gas-heater the combination of an outer shell with an inner shell arranged within the outer shell so as to leave a space between, such space forming a combustion-chamber, and ribs on the inner shell inclined from the vertical and projecting into such combustion-chamber. 80

4. In a gas-heater the combination of an outer shell, an inner shell, ribs on the outer shell inclined from the vertical, and oppositely-inclined ribs on the inner shell. 85

5. In a gas-heater the combination of an outer shell, substantially cylindrical, inclined ribs of diminished width from top to bottom on the lower portion of such outer shell, an inner shell having the upper part cylindrical and the lower part conical in form, ribs on the lower part of increasing width from top to bottom, and oppositely inclined with respect to the ribs on the outer walls. 95

6. In a gas-heater the combination of a lower combustion-chamber, a burner in such combustion-chamber, an upper combustion-chamber connected therewith with obstructions therein to divert the passage of the products of combustion therethrough, a smoke-pipe leading from the upper chamber, and a substantially straight flue leading from the lower chamber to such smoke-pipe. 105

7. In a gas-heater the combination of a combustion-chamber, a burner near the lower end of such chamber, a smoke-pipe leading from near the upper end of such chamber, and a single relatively small flue leading from a place near the burner to a place in the combustion-chamber near the smoke-pipe. 115

8. In a gas-heater, the combination of a horizontal, annular, hollow burner, a spiral spring in such burner an inlet leading thereto, and a hood device over such inlet to direct the incoming gas and air into the center of the spring. 120

9. In a gas-heater the combination of an outer shell, an inner shell, a burner, means for supporting such shells and burner, and a hollow draft and protecting device associated with the inner shell extending close to the floor, having a flaring part to protect the floor 130

from the heat of burner and an aperture on the under side thereof to receive air.

10. In a gas-heater the combination of a cylindrical outer shell with a substantially cylindrical inner shell, a circular burner, means for supporting the inner and outer shells and the burner, and a draft and protecting device comprising a hollow conical part associated with the inner shell and extending near to the floor 10 and a horizontal flange extending from the lower edge of the conical part, and a disk secured below such flange, and space therefrom to provide for the admission of air to the interior of the conical part.

15. 11. In a gas-heater the combination of a lower combustion-chamber of increasing width from top to bottom formed by walls having ribs thereon, a burner in such chamber, means for supporting the burner and the walls, an upper combustion-chamber having 20 a smoke-outlet, a series of transverse partitions therein, with differently-positioned apertures so as to make a circuitous passage-way for the products of combustion, and an air-chamber extending through such combustion-chambers.

12. In a gas-heater the combination of a lower combustion-chamber with a cylindrical outer wall and a circular inner wall of diminished diameter from top to bottom, ribs diversely inclined from the vertical on the respective walls, a burner in the chamber perforated so as to direct flames toward each 30 ribbed wall, an upper combustion-chamber 35 with circuitous passage-ways for the products of combustion, a flange extending part way across the passage between the upper and lower combustion-chamber, and a supporting

device for the burner and the walls of such chambers.

13. In a gas-heater, the combination of an inner and outer shell forming between them a combustion-chamber, ribs on such inner sides of such shells, an upper chamber or flue above the combustion-chamber, and a flange 45 on the inner shell extending part way across the chamber so as to narrow the outlet from the combustion-chamber to the upper chamber or flue.

14. In a gas-heater, the combination of a 50 combustion-chamber with a burner in such chamber, a smoke-outlet leading from such chamber and a relatively narrow inclosed flue extending from near by the burner into proximity to such outlet.

15. In a gas-heater the combination of a combustion-chamber with an air-chamber through such combustion-chamber, the containing-wall of such air-chamber being extended downwardly beyond the combustion-chamber and in proximity to the floor so as to draw the air for circulation through such heater from the lowest part of the room.

16. In a gas-heater the combination of a combustion-chamber with an air-chamber 65 through such combustion-chamber, the containing-wall of such air-chamber being extended downwardly in proximity to the floor and provided with a longitudinal extension to impede the radiation downward from the 70 burner.
